US0D1038786S

(12) **United States Design Patent** (10) Patent No.: **US D1,038,786 S**
(45) Date of Patent: ** Aug. 13, 2024

(54) **LIDAR**

(71) Applicant: **HESAI TECHNOLOGY CO., LTD.**,
Shanghai (CN)

(72) Inventors: **Kang Zhu**, Shanghai (CN); **Siyuan Liu**, Shanghai (CN); **Shaoqing Xiang**, Shanghai (CN)

(73) Assignee: **HESAI TECHNOLOGY CO., LTD.**,
Shanghai (CN)

(**) Term: **15 Years**

(21) Appl. No.: **29/870,641**

(22) Filed: **Feb. 1, 2023**

(30) **Foreign Application Priority Data**

Aug. 4, 2022 (CN) 202230507376.7

(57) **CLAIM**

The ornamental design for a lidar, as shown and described.

DESCRIPTION

FIG. 1 is a perspective view of a lidar showing my new design.

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The broken lines depict portions of the articles that form no part of the claimed design.

1 Claim, 7 Drawing Sheets
